Inventor:

Frank E. Thomes

UNITED STATES PATENT OFFICE.

FRANK E. THOMES, OF SOUTH PORTLAND, MAINE.

EQUIPMENT FOR SOFT-COAL-BURNING FURNACES.

Application filed October 11, 1926. Serial No. 140,897.

My invention relates in a general way to furnace grates, but more especially has to do with a type of grate adapted for use in burning bituminous coal and coke.

5 A specific object of my present invention is to provide better facilities for unloading the grate when it becomes necessary to dump the fire; and for this purpose I partially withdraw the grate proper from its supporting member so as to allow a free, unobstructed passage way from the fuel space in the furnace to the ash-pit, for clinkers, ashes or any foreign matter in the coal.

10 Another object is to supply draft-controlling means in connection with and in close proximity to the grate itself, the purpose of which I will fully explain herein-after in my specification.

15 Another important object is to reduce the grate area to such an extent that it embraces only a portion of the full area of the fuel-bed,—the remaining surface which is ordinarily utilized for grate purposes being closed to admission of air from the ash-pit 20 to the fuel space in the furnace. I have a definite reason for thus decreasing the grate surface and this I will make known later on in the description of my apparatus.

25 In the specification following, I have disclosed one embodiment, which, at the present time, I consider preferable to other possible forms of the invention; and in the drawings accompanying and made a part of this application and in which like characters of reference identify similar parts throughout all 30 the different views.

35 Fig. 1 is a fragmentary front sectional elevation of a boiler and base member showing my grate and grate carrier, also in sectional view;

40 Fig. 2 is similar to Fig. 1 except that the parts are shown in side sectional elevations; or on line 2—2, Fig. 1;

45 Fig. 3 is a plan of the grate, viewed from line 3—3, Fig. 1;

Fig. 4 is a sectional plan taken on line 4—4, Fig. 2, the grate elements not being shown.

50 Fig. 5 is a fragmentary enlarged cross section of the grate and damper slide, taken on line 2—2, Fig. 1;

55 Referring to Figs. 1 and 2, 1 represents the lower portion or the water leg of a boiler, 2 the base enclosing the ash-pit 3, and 3' the ash-pit door.

Suspended from the top flange 2' of the base is a fire-pot 4, preferably made in two parts, with the flange 4' thereof resting on the base flange 2'.

50 The body portion of the grate-carrier is cylindrical in form and depends into the ash-pit for a considerable distance. At its lower end it is provided with facilities for 55 slidable mounting a grate member 5 in grooves 6, and directly beneath and contiguous to this grate member is slidably mounted another grate element 7, operable in the grooves 8.

55 In grate 7 I provide openings 7' which match the openings 5' in the grate 5. Both 60 members, 5 and 7, have extended portions 5'' and 7'', respectively, and on these extensions are projections 9 and 10 by which the two 65 grate elements, singly or collectively, may be operated backwardly or forwardly along 70 their respective grooves, using for this purpose a poker or bent rod which is inserted in the holes in the projections.

75 At spaced intervals around the cylindrical body of the grate carrier 4 and formed in the 80 wall thereof, are vertical slots 11, and mounted, preferably, on the outer periphery of the carrier is a cylindrical sleeve 12, the latter having slots 13 which register with the slots 11 in the carrier 4. This sleeve is oscillatable on the body of the carrier so that the 85 slots 11 may alternately be open and closed. A handle 14 serves as means by which to oscillate the sleeve.

85 The structural features of my device having been set forth, I will describe its operation after first pointing out a few facts concerning the ordinarily accepted method of operating soft coal fires on conventional 90 type grates.

95 First: The grate, as usually constructed, extends over substantially the whole area of the fire-bed and air is permitted to penetrate the fuel over practically the whole surface of the grate. A certain amount of air is, 100 of course, necessary to establish and maintain proper combustion of the fuel, but a matter which has apparently escaped the attention of engineers and inventors is the waste of heat units incurred by allowing the 105 cool, or but slightly warm air from the ash-pit to come into direct contact with the inside shell of the water-leg of the boiler. This air absolutely lowers the temperature 110 of the boiler water and is therefore acting to

defeat the purpose for which the fuel is being burned.

In contrast to this, I bar the admission of air from the ash-pit to the fuel space at the marginal portions of the furnace by the interposition of the annular shaped flange 4' which extends completely there-around. And to further insure against possible air leaks at this point I make this flange serve as a seat or repository for ashes, represented in Figs. 1 and 2 by the character *a*, and this assists in sealing the partition between the ash-pit and fuel space in the furnace at the lower marginal portion thereof.

Second: The ash-pit door for heating-boilers will seldom be found completely closing the ash-pit to the entrance of air,—the door joint never being a tight fit, and, given a strong chimney draft, certain expedients must be resorted to to provide the proper check to the combustion of the fuel when the fire is to be run low or smouldering. Flue or funnel openings to the outside air and slides in the feed door are the usual forms for this service. But openings through the feed door tend to cool the boiler water and there is therefore a distinct loss of heat units.

30 My method of draft control contemplates providing supplemental means apart from the usual devices employed for this purpose and consists in general of sealing, more or less completely, the under side of the fuel-bed so as to prevent or control air communication between the fuel space and the space in the ash-pit.

The grate area in my device is decreased to a large extent from what is ordinary practice. I do this because by thus contracting the size together with placing the grate centrally of the furnace all air passing into the fuel must first come in contact with the hottest portion thereof, and so when this air finally reaches the walls of the furnace it is hot air instead of cold. Better combustion also takes place when the air mixing with the gases is hot, and very little smoke passes up the chimney.

50 The operation of the grate may be accomplished by a slight reciprocation of the grate 5, backwardly and forwardly, which will clear the top of the grate of the fine ash accumulation. Subsequent to an all night period of closed drafts it is well to withdraw the two members 5 and 7 simultaneously, which will have the effect of dumping the coarser elements,—as clinkers, slate or other foreign matter remaining unburned, into the ash-pit. It might be pertinently asked what becomes of the main portion of the fuel-bed, consisting of the coked and unburned material, after this dumping operation is performed. In explanation I will say that one characteristic of bituminous

coal is to coke or solidify into a practically homogeneous mass after being slightly heated or burned. This mass remains intact, suspended as it were, in the furnace by contact with its walls, so that this upper portion of the fuel-bed does not drop when the grate is removed to allow the ashes and clinkers to fall; and, after returning the grate to its working position, this top portion is broken up by a bar and falls to the grate, portions of it being aglow, and this forms, after new fuel has been added, the lower section of a new fuel-bed.

The apertures 11 in the depending portion of the grate support are employed largely to increase the air capacity of the furnace when it is desired to force the fire, but here, too, these openings are in many cases not absolutely essential for under ordinary conditions the air capacity through the grate is sufficient.

The invention chiefly consists in the three features,—first, the adaptability of the device to seal the lower, marginal portions of the furnace adjacent the water leg against the cooling effect of low temperature air, which, in ordinary furnaces rises from the ash-pit and impinges on the inner walls of the furnace; second, the provision made, and employed when necessary, to air-seal the grate in close proximity thereto, and third, the ability to completely withdraw the two grate elements to provide an open and unobstructed passage-way from the furnace space to the ash-pit for dumping the fire.

Having thus described my invention, what I claim is:

1. In equipment for soft-coal-burning furnaces, comprising in combination a furnace base member having an opening in the top thereof, a hollow upright member centrally disposed within said opening and having a plurality of apertures in the wall thereof, a horizontal flange extending outwardly from and around the wall of said hollow member and adapted to rest on the top of said base member, a frame subtended from said hollow member having a slide-way on each inner side thereof, a perforate grate element reciprocable in said slide-way and means to completely withdraw said grate element from said frame.

2. In equipment for soft-coal-burning furnaces, comprising in combination a furnace base member having an opening in the top thereof, a hollow member centrally located in said opening, the axis thereof being vertical, an outwardly extending flange on the upper end of said hollow member, said flange bearing on and supported by the top of said base member, upstanding ports in the wall of said hollow member, a frame depending from said hollow member, two perforate grate elements operable in said frame, one element above the other, and means whereby

either of the said grate elements may be reciprocated in said frame independently of the other.

3. In equipment for soft-coal-burning furnaces, comprising in combination, a furnace base member having an opening in its top, a hollow member having open ends located within said base member and having an outwardly extending circumferential flange bearing on the top of said base member, said hollow member having through its wall a plurality of upstanding, relatively long and narrow apertures, closing means for said apertures, said means acting in a direction transversely of said apertures, a frame subtended from said hollow member and having on the inner sides thereof two vertically spaced slide-ways, a perforate grate element operable in each of said slide-ways and in adjacent vertical relation, relatively, and means to reciprocate said grate elements in said slide-ways, said reciprocations effective to move said grate elements either singly or collectively.
- 25 4. In equipment for soft-coal-burning furnaces, comprising in combination, a furnace-supporting member having an opening in the top thereof of relatively smaller diameter

than that of the furnace, a long, upright cylinder disposed within said opening and depending for its full length into the space in said furnace-supporting member and having on its upper end a circumferential flange lying superjacent the top of said furnace-supporting member, a plurality of long, narrow ports in the wall of said cylinder and extending substantially the full length thereof, a sleeve completely surrounding the said cylinder and having ports therein to match those in said cylinder, means to oscillate said sleeve, a frame on the lower end of said cylinder, two vertically spaced slide-ways in said frame, a perforate grate element operable in each of said slide-ways, means to actuate said grate elements whereby either one, in coaction with the other, may be made to fully close or to partially uncover the perforations in the other, and means to slidably and completely withdraw either one or both of the two said grate elements from said frame.

Signed at Portland, county of Cumberland and State of Maine, this 8th day of June, 1927.

FRANK E. THOMES.
